UNITED STATES PATENT OFFICE.

JOHN K. McLAUGHLIN, OF PHILADELPHIA, PENNSYLVANIA.

WATER-HEATER.

No. 822,545.

Specification of Letters Patent.

Patented June 5, 1906.

Application filed January 31, 1906. Serial No. 298,847.

To all whom it may concern:

Be it known that I, JOHN K. McLAUGHLIN, a citizen of the United States, residing in the city and county of Philadelphia, State of Pennsylvania, have invented a new and useful Water-Heater, of which the following is a specification.

My present invention relates to water-heaters; and it consists of a novel construction of a heater unit in which the water or circulating fluid passing therethrough is always in contact with a heated surface.

It further consists of a novel construction of a unit composed of an upper and lower member having interposed therebetween a suitable diaphragm having a baffle-plate on opposite sides of said diaphragm and engaging the contiguous side of its outer disk member and novel means for leading the fluid to be heated into and out of the chambers formed between said diaphragm and the upper and lower disk members of the unit.

It further consists of a novel construction of a unit in which the circulating fluid is always exposed to a heated surface, and in addition this unit has passages therethrough, through which pass the flame and products of combustion.

It further consists of a novel construction of coupling connection suitably secured to the intermediate disk or diaphragm member whereby the units may be correlated and arranged according to the conditions and requirements and the circulating fluid may readily pass from one unit to the next unit in the series.

It further consists of novel features of construction, all as will be hereinafter fully set forth.

Figure 1 represents a perspective view of a fluid-heating unit embodying my invention, the same being viewed from its under side, but having a portion of the lower disk-casing removed. Fig. 2 represents a perspective view viewed from above, but having a portion of the upper disk-casing removed for convenience of illustration. Fig. 3 represents a sectional view of one of the units. Fig. 4 represents a top plan view of a portion of a unit having the upper disk-casing removed. Fig. 5 represents a sectional elevation showing one manner in which the units may be arranged in a water-heater.

Similar numerals of reference indicate corresponding parts in the figures.

Referring to the drawings, 1 designates a

heater unit or section, the same being provided with an upper casing or disk 2 and a lower casing or disk 3, said upper disk having a laterally-extending flange 4, which abuts against a flange 5, which latter extends angularly from a flange 6, extending laterally from the lower disk 3.

7 designates a diaphragm or dividing member the outer perimeter of which is seated between the flange 4 of the upper member 2 and the flange 6 of the lower member 3 and abutting against the flange 5, whereby a tight joint may be readily formed between the upper and lower members.

8 designates a threaded connection or coupling secured to the disk or diaphragm 7 by means of a bolt 9 and a nut 10 or equivalent devices.

11 designates a threaded connection of a similar character to the connection 8 and suitably secured to the opposite side of the intermediate member 7. The connection 8 is provided with a suitable shoulder 12, and the disk 2 is centrally apertured in order that when the parts are in assembled position said upper disk will abut against the shoulder 12 and have water-tight connection therewith. The lower connection 11 is provided with a similar shoulder 13, against which abuts the lower disk member 3 when the parts are in assembled position, said lower member 3 having a suitable aperture therethrough, whereby it may be readily placed in position on said connection or coupling. These connections may be squared or otherwise adapted to receive a suitable wrench, whereby the units may be readily connected or disconnected from the heating system, as desired.

14 designates a baffle-plate extending from the connection 11 and adapted to form a water-tight connection between the disk 7 and the lower disk 3. The circulating fluid passes through the inlet 15 into the connection 11 and is thence deflected through an opening 16, which is in proximity to or contiguous to the baffle-plate 14, which causes the fluid to be deflected and pass around the chamber formed between the center diaphragm 7 and the lower disk 3, thence through an opening 17 in the diaphragm 7, which is contiguous to the baffle-plate 14.

18 designates a baffle-plate similar to the baffle-plate 14 and forming a water-tight engagement between the connection 8, the diaphragm 7, and the upper disk 2 in a similar manner to that already described. The wa-

ter passing through the opening 17 is deflect-
ed by the baffle-plate 18 and passes around
the chamber formed between the upper mem-
ber 2 and the diaphragm 7 in the direction of
5 the arrows until it strikes the opposite side of
said baffle-plate 18 and is deflected thereby
through an opening 19 in the coupling connec-
tion 8. In order to increase the heating-
surface of the unit, the upper disk member 2
10 is suitably apertured, as at 20, and the lower
disk member is apertured in a like manner,
as at 21. The diaphragm 7 has suitable ap-
ertures 22 extending therethrough. These
apertures 20, 21, and 22 are in alinement
15 when the parts are in assembled position and
have secured therein a suitable tube or pipe
23, which is provided at each end with a
shoulder 24, whereby a water-tight connec-
tion may be formed between the central dia-
phragm and the upper and lower disk mem-
bers.

In Fig. 5 I have shown in sectional elevation
one manner in which the heater sections
or units may be arranged, although it will be
25 apparent that said sections may be otherwise
correlated and arranged and still be within
the scope of my invention. In this figure, 25
designates a burner or heating medium,
which may be of any usual or conventional
30 type, said burner being suitably supported
on a bottom casing 26, to which is attached
an outer casing 27.

28 designates a diaphragm or closure sup-
ported at the upper end of the outer casing
35 27 and having an opening 29 therethrough.

30 designates the top of the casing, having
a suitable opening 31 therethrough.

The operation will be readily apparent and
is as follows: The water or other fluid which it
40 is desired to heat enters through the pipe 32,
and passes through the inlet 15 into the cham-
ber 33 of the lower connection of the first heat-
ing section, to which the pipe 32 is secured.
The water then passes through the opening 16
45 into the chamber formed between the dia-
phragm 7 and the lower disk 3. It then
passes around said chamber in the direction of
the arrows (seen in Fig. 1) until it strikes the
baffle-plate 14 and is deflected thereby,
50 through the opening 17, into the chamber
formed between the upper disk 2 and the dia-
phragm 7. In this chamber it is deflected by
the baffle-plate 18 and passes around the
chamber formed between the diaphragm 7
55 and the upper disk member 2 until it strikes
the opposite side of said baffle-plate and is
deflected thereby, through the opening 19,
into the chamber 34 and thence through the
outlet 39 into the pipe 35. The water passes
60 from this connection 35 to the second heat-
ing section or unit, through which the water
circulates in the same manner as that already
described in connection with the first unit.

36 designates a pipe leading from the last
65 heating unit, said pipe being suitably con-

nected, by means of a coupling-nut or equiv-
alent device 37, with the distribution-pipe
38, by means of which the heated water is
conducted to a desired point of utilization.
The products of combustion surround on all
70 sides the different units and also pass through
the tubes 23 and escape at the top of the
heater through the ports or openings 29 and 31.

It will thus be seen that in my present con-
struction the heated products of combustion
75 not only completely surround the units, but
also pass therethrough, and the water or
other fluid passing through the heater will al-
ways be exposed to a heated surface, so that
the water or other fluid will be rapidly heated
80 in a very efficient, cheap, and reliable man-
ner. Since each heating unit will absorb the
heat in proportion to the amount of the ex-
posed surface, it will be evident that by in-
creasing the heating-surface the efficiency of
85 the unit is greatly increased.

It will be further apparent that the unit
may be very cheaply constructed and is in a
very compact form when the parts are in as-
90 sembled position and, further, that the units
may be correlated and arranged in any de-
sired manner, according to the results which
it is desired to attain and the condition and
requirements of the case.

It will be further apparent that while in
the present instance for convenience of illus-
tration I have shown the coupling member as
composed of two parts 8 and 11 and the in-
termediate diaphragm 7 as extending be-
tween these two coupling members this
coupling member may be formed of a single
piece of material having an intermediate dia-
phragm therein, in which case the diaphragm,
as 7, would extend only to the walls of the
coupling and the water would pass through
the unit in the same manner and the same
result would be obtained. I do not, there-
fore, desire to be limited to the construction
in which the coupling is composed of two
parts having the intermediate diaphragm
110 passing therethrough.

Having thus described my invention, what
I claim as new, and desire to secure by Let-
ters Patent, is—

1. In a heater unit, an upper and a lower
casing, a diaphragm having an aperture there-
through intermediate said casings, and form-
ing chambers therebetween, a coupling mem-
ber secured on each side of said diaphragm
and extending through the casing contiguous
thereto, each of said members having an
opening communicating with the chamber
contiguous thereto and means for deflecting
the water through said openings.

2. In a heater unit, an upper and a lower
casing, a diaphragm having an aperture
therethrough intermediate said casings and
forming chambers therebetween, a coupling
member secured on each side of said dia-
phragm and extending through the casing

contiguous thereto, each of said members having an opening communicating with the chamber contiguous thereto, and a baffle-plate extending from each of said members for deflecting the water through said openings.

3. In a heater unit, an upper and a lower casing, a diaphragm having an aperture therethrough intermediate said casings and forming chambers therebetween, a hollow member secured on each side of said diaphragm and extending through the casing contiguous thereto, each of said members having an opening therethrough communicating with the chamber contiguous thereto, a baffle-plate extending from one of said members on one side of said aperture and a baffle-plate extending from the other of said members on the other side of said aperture.

20 4. In a heater unit, an upper and a lower casing, a diaphragm having an aperture therethrough intermediate said casings and forming chambers therebetween, a hollow member secured on each side of said diaphragm and extending through the casing contiguous thereto, each of said members having an opening therethrough communicating with the chamber contiguous thereto, a baffle-plate extending from one of said members on one side of said aperture and a baffle-plate extending from the other of said members on the other side of said aperture, said members having their outer ends internally threaded.

35 5. In a heater unit, an upper and a lower casing, a diaphragm having an aperture therethrough intermediate said casings and forming chambers therebetween, a hollow coupling member secured on each side of said diaphragm and extending through the casing contiguous thereto, each of said members having an opening communicating with the chamber contiguous thereto, a baffle-plate extending from one of said members on one side of said aperture, and a baffle-plate extending from the other of said members on the other side of said aperture and each of said members having a shoulder against which the casing contiguous thereto abuts.

45 6. In a heater unit, an upper and a lower casing, a diaphragm having an aperture therethrough intermediate said casings and forming chambers therebetween, a coupling member secured on each side of said diaphragm and extending through the casing contiguous thereto, each of said members having an opening communicating with the chamber contiguous thereto, means for deflecting the water through said openings and means for permitting the products of combustion to pass through said casings and said diaphragm.

55 7. In a heater unit an upper and a lower casing, a diaphragm having an aperture therethrough intermediate said casings, and

forming chambers therebetween, a coupling member secured on each side of said diaphragm and extending through the casing contiguous thereto, each of said members having an opening communicating with the chamber contiguous thereto, means for deflecting the water through said openings, said casings and said diaphragm having a plurality of openings therethrough and tubes secured in said openings for the passage of the products of combustion.

8. In a heater unit, an upper casing having a laterally-extending flange, a lower casing having a laterally-extending flange from which latter a flange extends angularly, a diaphragm having an aperture therethrough intermediate said casings and forming chambers therebetween and having its perimeter seated between said lateral flanges and engaging said angular extending flange, a hollow coupling member secured on each side of said diaphragm and extending through the casing contiguous thereto, each of said members having an opening communicating with the chamber contiguous thereto, means for deflecting the water through said openings and aperture, and means for permitting the products of combustion to pass through the unit.

9. In a water-heater, a heating medium, a series of heating units in proximity thereto, a casing having an opening at its upper end, each of said units comprising an upper and a lower casing, a diaphragm having an aperture therethrough intermediate said casings and forming chambers therebetween, a coupling member on each side of said diaphragm and extending through the casing contiguous thereto, each of said members having an opening communicating with the chamber contiguous thereto, means for deflecting the water through said openings and means for permitting the products of combustion to pass through each unit.

10. In a heater unit, a casing having two communicating chambers therein, a coupling member extending through said casing, said member having a plurality of separate passages therethrough, one of said passages communicating with one of said chambers, and the other of said passages communicating with the other of said chambers.

11. In a heater unit, a casing, an apertured member therein forming two communicating chambers and a coupling member extending through said casing, said coupling member having a plurality of separate passages therethrough, one of said passages communicating with one of said chambers and the other of said passages communicating with the other of said chambers.
